Application February 5, 1941, Serial No. 377,443

5 Claims. (Cl. 179—18)

This invention relates to selecting and switching systems.

The objects are to improve the usefulness of automatic switching mechanisms by providing for the simultaneous establishment of a plurality of connections; to prevent interference between the separate connections that are being established simultaneously; to prevent double or other false connections; and to increase the flexibility and efficiency, and in other respects to improve selecting and switching systems and mechanisms.

Numerous types of coordinate switching systems have been devised heretofore for connecting incoming lines to outgoing lines. In these prior systems it is usually necessary to provide some means for serving one incoming line at a time, so that double connections will not result if a number of incoming lines are seeking attention simultaneously.

In accordance with the present invention advantages are realized over these prior switching systems by the provision of means for enabling a plurality of simultaneously calling incoming lines to be connected at the same time to a corresponding number of idle outgoing lines without interference or double connections. More specifically these advantages and also the foregoing objects are realized in a switching system comprising a plurality of discharge tubes arranged coordinate in horizontal and vertical rows, each horizontal row of tubes representing an incoming line and each vertical row of tubes representing an outgoing line. Any incoming line is connectable to any outgoing line by the operation of the discharge tube at the coordinate cross-point of the incoming and outgoing lines, the connected incoming line being guarded against subsequent connection to a second outgoing line by potential changes on the electrodes of all other tubes in the same horizontal row, and, similarly, the connected outgoing line being guarded against subsequent seizure by a second incoming line by potential changes on the electrodes of all tubes in the corresponding vertical row. The tubes are operated by potential impulses of different phases, the impulses of a particular phase being applied simultaneously to all tubes in a particular diagonal row, the impulses of the next phase being applied simultaneously to the tubes in the next diagonal row, etc., for the other phases. With this arrangement only one tube may be operated at a given instant in any horizontal or vertical row, but all tubes subject to an impulse of a given phase may be operated simultaneously provided the associated

incoming line is in a calling condition and the associated outgoing line is in a selectable condition. The advantage of this method of operating only those tubes which lie in the same diagonal row in the switching mechanism is that a plurality of connections may be established simultaneously through the switching mechanism without any danger of interference and without obtaining any false connections.

10 The foregoing and other features and advantages of this invention will be described more fully in the following detailed specification.

In the drawings accompanying the specification:

15 Figs. 1 and 2 taken together illustrate a coordinate switching mechanism incorporating the features of this invention;

Fig. 1 shows a plurality of horizontal and vertical rows of discharge tubes for establishing connections between incoming and outgoing lines;

20 Fig. 2 shows an impulse generating mechanism for producing the operating impulses for the discharge tubes; and

25 Fig. 3 illustrates an alternative form of the switching mechanism.

The switching mechanism disclosed herein may be used for a wide variety of purposes. It may serve to establish connections in telephone, 30 telegraph or other communication systems between subscribers' lines or between said lines and links, trunks or other connecting circuits; it may serve to establish connections between incoming trunks and outgoing trunks; or it may be used 35 for connecting lines, links, trunks or other circuits to switch controlling or marker mechanisms, such as those used in automatic telephone systems. And, as above suggested, it may be used for numerous other purposes.

40 Referring particularly to the drawings, the switching mechanism disclosed herein serves to establish connections between a number of incoming lines 101, 102, 103, 104 and a number of outgoing lines 105, 106, 107, 108. While only

45 four incoming lines and four outgoing lines are illustrated, it will be obvious that this number may be increased and that the capacity of the switching mechanism will depend upon the specific use to which it is put.

50 Each incoming line is represented in the switch by a horizontal row of space-discharge tubes and associated connecting relays. Similarly, each outgoing line is represented in the switch by a vertical row of tubes and relays. For example, lines 101, 102, 103, 104 are represented

respectively by the horizontal rows of tubes 111, 112, 113, 114; and the outgoing lines 105, 106, 107, 108 are represented respectively by the vertical rows of tubes 115, 116, 117, 118. The anode of each tube is connected to the winding of a connecting relay associated therewith, and the windings of all connecting relays are connected to the positive pole of battery 182. For example, the anodes 121, 122, 123, 124 of tubes 125, 126, 127, 128 are connected respectively to the relays 129, 130, 131, 132, and these relays are connected over the common conductor 133 to the positive pole of battery 182. The cathodes of all tubes in each vertical row are connected over a common conductor and through a common resistance to the negative pole of battery. For example, cathodes 134, 135, 136, 137 of tubes 125, 138, 139, 140 are connected over the common conductor 141 and the common resistance 142 to the negative pole of battery 143. The screen or controlling grid elements of the tubes in each horizontal row are connected together and to the positive pole of battery. In the horizontal row 111 the control grids 144, 145, 146, 147 are connected over conductor 148 through the contacts of a control relay 183 and resistance 184 to the positive pole of battery 185; and the control grids of the tubes in the remaining horizontal rows 112, 113, 114 are similarly connected. The starting electrodes of the tubes, which co-operate with the cathodes to form the ionizing gaps, are connected to the impulse conductors 204 from the phase impulse generator 205.

These connections are so chosen that all of the tubes in a diagonal row are connected in multiple to the same impulse conductor. In the switch mechanism illustrated there are seven diagonal rows of tubes. The first row contains the single tube 125; the second row contains tubes 138 and 126; the third row contains tubes 139, 149 and 127; the fourth row contains tubes 140, 150, 151 and 128; the fifth row contains tubes 152, 153 and 154; the sixth row contains tubes 155 and 156; and the seventh row contains the single tube 157. The starting electrode 158 of the tube 125 in the first diagonal row is connected through resistor 159 to the No. 1 phase impulse conductor 206; the starting electrodes 160 and 161 of tubes 138 and 126 are connected through resistors to the No. 2 phase impulse conductor 207; the starting electrodes 162, 163, and 164 of the three tubes in the third diagonal row are connected through individual resistors to the No. 3 phase impulse conductor 208; and in like manner the starting electrodes of the tubes in the fourth, fifth, sixth and seventh rows are connected respectively to the impulse conductors 209, 210, 211 and 212.

The impulse generator 205, which may be of any suitable type, is designed to produce a series of impulses of different phases in response to each cycle of the voltage wave of the energizing source 213. The source 213 may have any suitable frequency, and the generator 205 responding to this source produces in each cycle of the wave a series of seven positive impulses, each spaced in time a definite interval from the preceding impulse. While the invention is not limited to the use of any particular type of impulse generator, reference may be had, for an understanding of the manner in which these impulses may be generated, to the application of W. H. T. Holden, Serial No. 361,536, filed October 17, 1940, and the patents to Holden No.

2,285,815 of June 9, 1942, and No. 2,252,766 of August 19, 1941.

The discharge tubes used in the switching mechanism illustrated herein may be of any well-known type. They may have hot or cold cathodes, screen or other control electrodes or separate starting electrodes and gaps; they may be filled with gases such as argon and neon.

A description will now be given of the detailed operation of the selecting system. Assume first that a calling condition appears on some one of the incoming lines, such as line 101, and that no calling condition appears on any of the other incoming lines at this time. Assume also that all of the outgoing lines 105, 106, 107 and 108 are idle. The calling condition on line 101 causes the operation of relay 183 in any well-known manner, and the relay 183 connects the positive pole of battery 185 through the resistor 184 to conductor 148. Thus the control grids 144, 145, 146 and 147 of the row of tubes 111, in which the calling line 101 appears, are raised to the positive potential of the battery 185. Assume that at this particular instant the generator 205 has just completed the delivery of an impulse of phase No. 1 and is about to deliver the next phase impulse over conductor 207. When this next impulse, phase No. 2, appears on the conductor 207, it is applied simultaneously through resistors 165 and 166 to the starting electrodes 160 and 161 respectively of tubes 138 and 126. The starting gaps of both tubes ionize in response to this impulse. The circuit for ionizing the gap 135-160 may be traced from the negative pole of battery 143, resistor 142, conductor 141, cathode 135, starting electrode 160, resistor 165 to conductor 207 on which the positive potential impulse is present. The circuit for ionizing the gap 167-161 of tube 126 may be traced from the negative pole of battery 168, resistor 169, conductor 170, cathode 167, starting electrode 161, resistor 166 to the impulse conductor 207 on which the negative impulse is present. Although the control gap of the tube 138 ionizes, ionization does not transfer to the main anode of the tube since no potential exists on the control grid 171. On the other hand the control grid 145 of tube 126 in the row serving the calling line 101 is at the potential of battery 185, and the ionization produced in the control gap transfers to the main anode 122. Current now flows in a circuit traceable from the positive pole of battery 182, conductor 133, winding of relay 130, anode 122, cathode 167, conductor 170, resistor 169 to the negative pole of battery 168. As soon as ionization transfers to the main anode, current flows from battery 185 through the resistor 184, conductor 148, grid 145, cathode 167, thence through resistor 169 to the negative pole of battery 168. The flow of current through the resistor 184 lowers the positive potential applied to the control grids of all other tubes in the row 111, so that ionization cannot transfer from the starting gap to the main anode. Thus the operation of one tube in the horizontal row 111 disables all of the other tubes in the same row. Similarly the flow of current through the common resistor 169 lowers the negative potential applied to the cathodes 172, 173, 174 of all other tubes in the vertical row 116 so that ionization in the control gap of any one of these tubes is prevented. Thus the operation of any tube in the vertical row 116 disables all remaining tubes in the same row. The flow of current in the main anode circuit

of the operated tube 126 causes the operation of relay 130, which establishes a connection between the conductors of the calling incoming line 101 and the selected idle outgoing line 106. As long as this connection continues the line 101 is guarded against a double connection with another outgoing line by means of the altered potential on the control grids of all tubes in the horizontal row 111. Also the selected outgoing line 106 is guarded against selection by another incoming line by means of the altered potential on the cathodes of all tubes in the vertical row 116.

Assume next that a plurality of incoming lines, such as lines 101, 102 and 104, are calling simultaneously and that an equal number of the outgoing lines are idle at the time, such as lines 105, 107 and 108.

When lines 101, 102 and 104 call, the associated relays 183, 186 and 187 operate. Relay 183 applies positive potential from battery 185 through resistor 184 to the control grid of the tubes in the horizontal row 111; relay 186 applies positive potential through resistor 188 to the control grids of the tubes in the horizontal row 112; and relay 187 applies positive potential through resistor 189 to the control grids of the tubes in the row 114. Assume also that the generator 205 at this moment is about to deliver a potential impulse of phase No. 4 over impulse conductor 209. When this impulse appears on conductor 209, it is applied through resistors 175, 176, 177 and 178 to the starting electrodes of the respective tubes 140, 150, 151 and 128 comprising a diagonal row. The starting gaps of these tubes ionize in response to this potential impulse, and ionization transfers to the main anodes of tubes 140, 151 and 128 since the control grids of these tubes are at positive potential. No transfer takes place, however, in the tube 150.

Anode current now flows in the discharge circuits of tubes 140, 151 and 128, and the associated relays 178, 179 and 132 operate. Relay 178 connects the calling incoming line 104 to the idle outgoing line 105; relay 179 connects incoming line 102 to outgoing line 107; and relay 132 connects incoming line 101 to the outgoing line 108. The flow of grid current through the common resistors 184, 188 and 189 alters the potential on the grids of the tubes in the corresponding rows to prevent the discharge of another tube in any one of these rows, thereby protecting the lines 101, 102 and 104 from subsequent connection to another outgoing line. Similarly the flow of discharge current through the common resistors 142, 180 and 181 alters the potential on the cathodes of all the tubes in the vertical rows 115, 117, and 118 to prevent another incoming line from being connected to either of the selected outgoing lines 105, 107 and 108.

Thus the application of a phase impulse of a single phase to the corresponding diagonal row of discharge tubes may result in the simultaneous connection of the entire group of calling incoming lines to corresponding outgoing lines. If, however, all of the calling incoming lines are not represented in the diagonal row to which an impulse is being applied at the instant the calls appear, as many of the calling lines will be served as there are idle outgoing lines represented in said diagonal row. Presently, however, impulses of the following phases will be applied in succession to the succeeding diagonal rows, and

the remaining calling lines will then be served. To explain this operation assume that lines 101, 102 and 103 call simultaneously and that the next phase impulse is applied to the diagonal row containing the single tube 125. If the outgoing line 105 is idle at this moment, tube 125 discharges, and the calling line 101 is connected to line 105. An instant later the next phase impulse is applied to tubes 138 and 126. Both of these tubes, however, are disabled by the operation of tube 125, and neither of them discharges. An instant later an impulse is applied to tubes 139, 149 and 127. In this diagonal row tubes 139 and 127 have been disabled by the operated tube 125, but tube 149 now discharges, provided the outgoing line 106 is idle, and the second calling line 102 is thereby connected to the line 106. Subsequently a phase impulse is applied to the diagonal row containing tubes 152, 153 and 154, and tube 153 operates, provided the circuit 107 is already idle, and the third calling line 103 is connected to the outgoing line 107.

The connections established from the calling lines to the called lines may be held in any suitable and well-known manner by maintaining the connecting relays in an energized condition. If desirable, the line relays 183, 186, etc., may be disconnected in the usual manner by means of cut-off relays.

If desirable the switching tubes disclosed in Fig. 1 may be replaced by tubes having separate control gaps. A single row 300 of switching tubes of this type is illustrated in Fig. 3. For example, the tube 301 is provided with a main anode 302, a main cathode 303 and an ionizing gap comprising a starting anode 304 and a starting cathode 305. When an impulse of phase No. 1 is applied to the starting anode 304, the starting gap ionizes, and ionization transfers to the main anode 302. Current now flows from the positive pole of battery 306 through the contacts of the operated relay 307, inductor 308, anode 302, cathode 305, resistor 309, to the negative pole of battery 310. The voltage drop in the resistor 309 alters the potential on the starting cathodes of all other tubes in the same vertical row to prevent a second tube from ionizing. Shortly after the initial transfer of ionization a transfer takes place between the main anode and main cathode of the tube, and current now flows from the main anode 302 to the cathode 303 thence through the work relay 311 to the negative pole of battery. When discharge current is rising in the circuit above traced, the inductor 308 produces a voltage drop which is applied to the anodes of all tubes in the horizontal row 300 to render them ineffective. As soon as the current in the discharge circuits reaches its steady state, the drop due to the resistance of the element 308 lowers the positive potential on the anodes in the row 300 to prevent a second tube from operating.

During the time a connection is maintained, discharge current flows from the main anode to the main cathode and also to the starting cathode. This continued flow of current through the common resistor 309 in the circuit of the starting cathodes lowers the negative potential of all starting cathodes in the corresponding vertical row of tubes to prevent a second one of these tubes from ionizing when phase impulses are applied to the starting anodes.

What is claimed is:

1. The combination in a selecting system of a plurality of incoming circuits, a plurality of outgoing circuits, each incoming circuit being con-

nectable to each outgoing circuit, a plurality of discharge devices arranged in coordinate series, the several series of devices in one coordinate direction serving respectively the several incoming circuits, the several series of devices in the other coordinate direction serving respectively the several outgoing circuits, means for producing impulses, and circuit means for applying said impulses simultaneously to a group of said devices comprising one device in each of a plurality of series in both coordinate directions, the devices of said group which correspond to calling incoming circuits and to selectable outgoing circuits operating simultaneously in response to said impulses to effect connections between the calling incoming circuits and the respective selectable outgoing circuits.

2. The combination in a selecting system of a plurality of incoming circuits, a plurality of outgoing circuits, said incoming circuits being connectable to said outgoing circuits, a plurality of discharge devices arranged in coordinate rows, the several rows of devices in one coordinate direction serving respectively the several incoming circuits, the several rows of devices in the other coordinate direction serving respectively the several outgoing circuits, means for producing impulses of a plurality of phases, means for applying impulses of the successive phases respectively to successive groups of said devices, each group of devices comprising one device in each of a plurality of rows in one coordinate direction and one device in each of a plurality of rows in the other coordinate direction, the devices of each group which correspond to calling incoming circuits and to selectable outgoing circuits operating simultaneously in response to the impulses applied thereto to effect connections between the incoming circuits and the outgoing circuits.

3. The combination in a switching system of a plurality of incoming circuits, a plurality of outgoing circuits, said incoming circuits being connectable to said outgoing circuits, a plurality of discharge tubes arranged in coordinate rows, the several rows of tubes in one coordinate direction being associated respectively with the several incoming circuits, the several rows of discharge tubes in the other coordinate direction being associated respectively with the outgoing circuits, means for producing impulses of a plurality of different phases, circuit means for applying the impulses of the successive phases respectively to successive groups of tubes, each group of tubes

comprising a tube in each of a plurality of rows in both coordinate directions, the tubes of any one of said groups which correspond to calling incoming circuits and selectable outgoing circuits operating in response to said impulses, means responsive to the operated tubes for connecting the incoming circuits to the outgoing circuits, and means effective in response to the operation of one of said tubes for rendering ineffective the remaining tubes in the coordinate rows containing the operated tube.

4. The combination in a switching system of incoming lines and outgoing lines, said incoming lines being connectable to said outgoing lines, a plurality of discharge tubes arranged in horizontal and vertical rows, the tubes of said horizontal and vertical rows forming diagonal rows, the horizontal rows serving the respective incoming lines and the vertical rows serving the respective outgoing lines, means for producing impulses, circuit means for applying said impulses simultaneously to the tubes of a diagonal row, the tubes of said diagonal row which correspond to calling incoming lines and idle outgoing lines operating simultaneously in response to said impulses, and means responsive to the operated tubes for connecting the incoming lines to the outgoing lines.

5. The combination in a switching system of incoming lines and outgoing lines, said incoming lines being connectable to said outgoing lines, a plurality of discharge tubes arranged in coordinate rows, the tubes of said coordinate rows forming diagonal rows, the tubes of the rows in one coordinate direction serving the respective incoming lines and the tubes of the rows in the other coordinate direction serving the respective outgoing lines, means for producing impulses of a series of different phases and for repeating said impulses cyclically, the impulses of the successive phases corresponding respectively to the successive diagonal rows of discharge tubes, circuit means for applying the impulses of each phase simultaneously to the tubes of the corresponding diagonal row, the tubes of any diagonal row which at the time the impulses are applied thereto correspond to incoming lines that are in a calling condition and to outgoing lines that are in an idle condition operating simultaneously in response to said impulses, and means responsive to the operated tubes for connecting the incoming lines to the outgoing lines.

CARLYLE V. PARKER.
